UNITED STATES PATENT OFFICE.

EDWARD C. MEIER, OF PHOENIXVILLE, PENNSYLVANIA.

DESIGN FOR A FURNACE-TILE.

47,930.

Specification for Design.

Patented Oct. 5, 1915.

Application filed March 16, 1915. Serial No. 14,818. Term of patent 14 years.

To all whom it may concern:

Be it known that I, EDWARD C. MEIER, a citizen of the United States, residing at Phoenixville, in the county of Chester and State of Pennsylvania, have invented a new, original, and ornamental Design for Furnace-Tiles, of which the following is a specification, reference being had to the accompanying drawing, forming a part thereof.

The figure is a perspective view of a furnace tile, showing my new design.

I claim:

The ornamental design for a furnace tile, as shown.

EDWARD C. MEIER.

Witnesses:

C. R. ZIEGLER,

S. W. FOSTER.
